UNITED STATES PATENT OFFICE.

CHARLES H. SMOOT, OF MAPLEWOOD, NEW JERSEY.

DESUPERHEATER.

Application filed January 18, 1927. Serial No. 161,940.

My invention consists in an improved and simplified desuperheater that is automatic in action and thoroughly safe in operation.

My desuperheater automatically reduces the superheat of steam in any desired amount by permitting water to flow directly into the steam in quantities proportional to the volume of steam to be desuperheated.

The various novel features of my desuperheater and the advantages pertaining thereto can best be understood from the following description when taken in consideration with the accompanying drawing in which I have illustrated my desuperheater in the form best known to me and in combination with apparatus with which it may be advantageously employed.

Referring to the drawings a high pressure steam main 1 carrying superheated steam is connected to the low pressure steam main 2 through tie-line T provided with emergency shut-off valves V, reducing valve 3 and desuperheater S hereinafter to be described. The reducing valve 3 permits steam from the main 1 to flow through the line T and desuperheater S to the header 2 to supplement the low pressure generators during peak load. The valve 3 is preferably controlled automatically and is shown in the drawing, being controlled in response to the steam pressure in the header 2 by means of a regulator 4 tending to open and close the valve 3 with decreasing and increasing pressure respectively in the main 2. The specific construction and location of the regulator 4 is immaterial to my present invention. For purposes of illustration I have shown the regulator 4 as a cylinder within which is a piston 5, subjected to the pressure within a chamber 6, the chamber 6 being in communication with the header 2 by means of the conduit 7 provided with a cut-off valve 8. A spring 9 pushes upon the piston 5 to oppose the pressure in the chamber 6. Attached to the piston is a rod 10 linked to a lever 11 which is pivoted at 12 and carries a member 13, the position of which determines the degree of opening of the valve 3. When the load on the low pressure generators increases the pressure within the chamber 6 decreases allowing the spring 9 to raise the piston 5 and rod 10. The movement of the rod 10 is transmitted to the member 13 by the lever 11 to open the valve 3 proportionately to the increase in load in the main

2. Similarly a decrease in load results in a proportionate closing of the valve 3.

I will now describe the various parts of my desuperheater. A length of the tie-line T is made U-shaped, with the vertical sections 14 and 16 and the horizontal section 15. A Venturi constriction is made in the section 16, the throat 17 of this constriction being at the lower end of the section. Terminating within the throat 17 are nozzles 18 attached to the end of a pipe 20. The pipe 20, having the hand regulating valve 21 leads from the water space of a reservoir 19 through the wall of the section 15. The water in the reservoir is maintained substantially at the level of the throat 17 by means of a float 22 controlling at 23 the feed of water to the reservoir from the supply line 24. In the supply line 24 there is provided a valve 25, the control of which is effected by the regulator 4 through a rod 26 linked to the lever 11 operating to open or close the valve 25 proportionally with the valve 3.

The space above the water in the reservoir 19 is connected by pipe 27 to the tie-line T just beyond the vertical section 16. The reservoir 19 is provided with an overflow pipe 28 leading from a point at the level of the nozzles 18 to a sump 29 through a trap 30. When desired the water may be drained from the reservoir through a pipe 31 provided with the cut-off valve 32 and leading into the overflow pipe 28. To prevent any possible collection of water in the horizontal section 15 of the tie-line, a drain 33 provided with the cut-off valve 34 leads from this section 15 to the sump 29. A separator 35 is inserted in the tie-line T beyond the superheater, with a drain 36 leading into the water space of the reservoir and provided with the cut-off valve 37.

The theory and operation of the apparatus above described is as follows:

When the steam pressure momentarily falls in the header 2 and chamber 6 of the regulator 4, indicating an increase in load on the low pressure generators, the valve 3 is opened sufficiently by the regulator 4 to permit steam at reduced pressure to flow through the tie-line to maintain the pressure in the header 2 at the desired value. At the same time the regulator 4 opens the valve 25 to permit the flow of water to the reservoir. The valve 25 serves to roughly proportion the flow of

water through the pipe 24 to the steam flow through the tie-line, as well as to prevent flooding of the device with water through leakage or other cause during time of no steam flow. The highly superheated steam at reduced pressure flows through the Venturi constriction in the section 16 where the increase in flow at the throat 17 causes a reduction in static pressure of the steam at this point, which pressure increases again as it reaches the end of the section 16. The pressure above the water in the reservoir will therefore be greater than that within the throat 17 and as the level of the water is maintained at the level of the throat, the difference in these pressures will be a measure of the steam flow through the tie-line. This pressure difference will cause water to flow through the line 20 from the reservoir and out as spray from the nozzles 18 into the steam in amount proportional to the quantity of steam flowing through the line. The ratio between the flow of steam and flow of water may be varied by adjustment of the valve 21, the setting of the valve depending upon the degree of superheat maintained in the high pressure header and that desired in the low pressure header. For a given setting of this valve 21 the apparatus therefore operates to automatically supply a given quantity of water to a given quantity of steam delivered through the tie-line; a larger flow of steam automatically receiving proportionately larger supply of water and similarly a smaller flow of steam receiving the proportionately smaller quantity of water resulting in each case in the same reduction in superheat.

As herein illustrated and described my superheater is preferably employed in combination with an automatically controlled reducing valve. My present invention however is primarily concerned with the desuperheater itself and is not limited to the particular combination in which it has been described, except as to such claims as may refer to other features of the combination.

It is apparent that my apparatus provides a simple and efficient means for automatically reducing the superheat of steam by any desired amount, and that further this degree of desuperheating may be adjusted to any value desired. An important feature of my desuperheater is that it accurately proportions the flow of water to the flow of steam without requiring any regulator other than a simple float for maintaining constant the water level in the reservoir.

I claim:

1. A desuperheater for automatically reducing the superheat of steam flowing through a conduit, including a Venturi section in said conduit, an enclosed reservoir, means for maintaining water at a constant level in said reservoir, a pipe connecting the

water space of said reservoir with a point within the throat of said Venturi section, and a second pipe connecting the space above the water in said reservoir with a point in said conduit removed from said Venturi section. 70

2. Means for desuperheating steam including a conduit for the flow of steam therethrough having a Venturi constriction in a vertical section thereof, an enclosed reservoir, means for maintaining water in said reservoir at approximately the level of the throat of said constriction, a pipe connecting the space above the water in said reservoir with a point in said conduit beyond said constriction and a connection from the water space of said reservoir terminating in nozzles within the throat section of said Venturi constriction. 75 80

3. Apparatus as in claim 2 wherein the pipe leading from the water space of the reservoir to nozzles within the throat of the Venturi constriction in the tie-line is provided with a manually adjustable regulating valve. 85 90

4. Means for desuperheating steam flowing through a conduit including a Venturi constriction in a vertical section of said conduit, an enclosed reservoir, a water supply line leading to said reservoir, means for maintaining constant the water level in said reservoir, a pipe connecting the water space of said reservoir with the throat section of said Venturi constriction and means for inducing a flow of water through said pipe in direct proportion to the flow of steam through said conduit. 95 100

5. Apparatus as in claim 4 including means for adjusting the ratio between the flow of steam and the induced flow of water. 105

6. In a steam installation generating high pressure superheated steam and low pressure steam and having headers for the same, the combination comprising a tie-line joining said headers and provided with a reducing valve, a Venturi constriction in a vertical section of said tie-line, an enclosed reservoir for water, a water supply line leading into said reservoir and provided with a valve, a mechanical interlock between the valve in the tie-line and said last mentioned valve for controlling both valves in unison, a pipe connecting the water space of said reservoir with the throat of said Venturi constriction and a pipe connecting the space above the water in said reservoir with another portion of said tie-line. 110 115 120

7. Apparatus as in claim 6, wherein the pipe leading from the water space of the reservoir into the throat section of the Venturi constriction is provided with an adjustable regulating valve and where said pipe terminates in nozzles within said throat section. 125

8. Apparatus as in claim 6 wherein means 130

are provided for maintaining the water in said reservoir substantially at the level of the throat of said Venturi constriction.

9. A desuperheater for steam, including a conduit for the flow of steam provided with a Venturi constriction in a vertical section thereof, an enclosed reservoir, a water supply pipe and drain and overflow pipes for said reservoir, a drain pipe for said steam conduit located below said Venturi constriction, a separator in the steam conduit be-

yond said constriction and provided with a drain leading into the water space of said reservoir, a pipe connecting said reservoir with the throat of said constriction and 15 means for inducing a flow of water from said reservoir through said last mentioned pipe in direct proportion to the flow of steam through said conduit.

In testimony whereof, I have signed my 20 name to this specification.

CHARLES H. SMOOT.
